REVERSIBLE FLOW FAN

Edgar R. Troxell, Jr., Bronxville, N. Y.

Application May 20, 1950, Serial No. 163,286

3 Claims. (Cl. 230—42)

My invention relates to means and method of room ventilation and particularly as applied to overhead window ventilators for offices, although generally adaptable to any window, transom, doorway or other suitable opening.

At present in most spaces having double hung windows, ventilation is attempted by raising the lower sash a short distance, with or without a so-called window guard. Such opening, being in or near the breathing zone, is neither the proper level at which to admit outdoor air, except perhaps in warm weather, nor, at any time, the level at which smoke, odors and vitiated air can best be expelled. As is well known, this method is dependent upon outside wind pressure which, in different directions, either causes drafts from the crack opened between the upper and lower sashes, as well as the opening itself, or draws air out at these points. In the latter case, the replacement air may come from an unsatisfactory source and a large amount of heat be lost without producing the desired ventilation of the space. In any case, this method is fundamentally unsound in principle as it (1) causes drafts in cold weather, (2) leaves a blanket of warm, vitiated air pocketed above the openings, and (3) lacks definite control.

Means and method, according to my invention, are primarily for positive, winter ventilation although adaptable also for summer ventilation as well as for distributing and diffusing conditioned air. The primary action of my device is to draw in, mechanically, a controllable amount of untempered outdoor air and spread it horizontally in a fan shaped stratum or spray near the ceiling of the space served. At the same time, by mechanical means as well as by induction, to spread a similar, separate stratum or spray or blanket of room air immediately under the stratum of outside air. If the upper stratum is colder, and hence heavier, than the underneath stratum of room air, the former must and will fall and, in so doing, commingle and diffuse with the room air before reaching the breathing zone.

It is emphasized that by the use of the means and method of my invention the introduction of air at a lower temperature than that of the room or space served, is made positive and controllable and that its action, by blanketing the colder air introduced, with a separate stratum of warmer air underneath, prevents the colder air falling before being completely commingled and diffused with the room air. Also that the use of my device, by drawing in a controllable quantity of outdoor air and projecting it, at controllable velocity, in a fan shaped stratum or spray in a horizontal direction near the ceiling of the space served, gives wide distribution and thorough diffusion of the air used for ventilation.

In such spaces as this device is designed to serve, it may be desirable at times to exhaust heat, smoke, odors or vitiated air from the upper strata of said space. As a matter of fact, alternating supply and exhaust action may well be found the most satisfactory method of securing desired results, particularly in warm weather when other windows are open but when there is little or no

2

natural air movement. To that end, in this device according to my invention, a revolvable inner fan-housing, manually turned to its alternate positions, accomplishes this complete reversal of air movement, viz., supply or exhaust. To accomplish these results, I provide a motor-driven, double disk-type centrifugal fan in a suitable two-way housing, fastened to a conditioned air duct or adjacent the top of a window which is opened sufficiently for the purpose. A revolvable inner fan-housing, in one position, provides discharge of air drawn from outside, either from a duct or from outdoors, as the case may be, into the room in a fan shaped stratum. Simultaneously, it provides for discharge of a similar separate fan shaped stratum of room air immediately under the first mentioned stream.

Thus a device according to my invention provides (1) means for introducing artificially chilled air or untempered outside air into a space without drafts, (2) utilization, in cold weather, of waste heat which otherwise stratifies at the top of a room, (3) more uniform heat distribution in a space, and (4) thorough distribution and diffusion of the air used for ventilation.

When the revolvable inner fan housing is manually turned to its alternate position, air from the top of the room is positively exhausted outdoors when the device is properly arranged at the top of a window, to remove smoke, odors etc.

A device of my invention comprises an outer flat, box-like housing, a motor of controllable speed affixed thereto having a shaft extending vertically into the housing, a centrifugal fan mounted on said shaft, said fan having a central separation disk at right angles to the motor shaft, with blades mounted thereon, above and below said disk, so as to provide two separate streams or strata of discharged air, one above the other, and permitting two separate intakes to said blades, one from above and the other from below the fan disk.

Within said outside housing is an inner housing comprising a semi-circular member surrounding approximately one-half of the periphery of said fan and revolvable through 180 degrees to provide either (1) discharge of air from both sets of blades into the room or (2) discharge of air from both sets of blades through a portion of the outside housing into the outdoor air. In both instances, the lower set of fan blades draws air from the upper part of the room through a grille forming a part of the lower face of the fan housing. Intake to the upper set of fan blades is determined by a second semi-circular member of the revolvable inner fan housing. This portion is fixed to but diametrically opposite the first named member and extends vertically between a plane near the top of the upper fan blades and the top plate of the outer housing.

The function of the inner housing is such that, in one position, it causes both sets of fan blades to discharge air into the room, the upper blades drawing air through a portion of the outside housing from outside. Manually revolved through 180 degrees to its other operating position, this inner housing causes both sets of blades to discharge through a portion of the outside housing to the outside, both sets of blades drawing air from the upper part of the room.

An object of my invention is to provide low cost and effective means and method for the ventilation of small offices and other rooms having outside windows.

A further object is to provide positive controlled ventilation without drafts using tempered or untempered or outdoor air.

Another object of the present invention is to provide a centrifugal fan contained in a two way, two part housing, one part of which housing is revolvable within the other to regulate and control the direction of intake and of dis-

charge of air by the fan for the purpose of either supply or exhaust of air.

Still another object is to provide means whereby outside air projected into a space by the fan may be blanketed underneath from the living zone of said space with a separate discharge by the fan, of air taken from the top of the space itself, thereby forcing the outside air to commingle with space air before reaching the breathing zone of the space.

A still further object of my invention is to provide a fan and housing therefor such that outside tempered or untempered air discharged into a space may be raised in temperature by waste heat otherwise stratified in the upper portion of the space itself and commingled with space air before reaching the breathing zone of the space.

With the foregoing and other objects in view, as will be apparent to those skilled in the art as the description proceeds, my invention resides in the combination and arrangement of parts and in the details of construction described in the specification and particularly pointed out in the appended claims, it being understood that changes in the particular embodiment of my invention may be made within the scope of what is claimed without departing from the spirit of the invention. I intend no limitation other than those of the claims when fairly interpreted in the light of the full disclosure and the present state of the art.

Referring now to the accompanying drawing illustrative of a preferred embodiment of my invention,

Fig. 1 is a sectional side elevational view showing a form of ventilator arranged to draw in and diffuse outside air; Fig. 2 is a sectional view similar to Fig. 1 with the same ventilator arranged to exhaust inside air; Fig. 3 is a perspective sketch illustrative of the inner revolvable housing; Fig. 4 is a side elevation of the part shown in Fig. 3; Fig. 5 is a bottom view of the fan housing, with motor removed; Fig. 6 is a fragmentary top view showing the fan air cut-off operable on exhaust operation; Fig. 7 illustrates in elevation a complete window installation viewed from the space served.

Similar reference numerals refer to similar parts in the several views.

Turning now to Figs. 1 and 2, a motor 10 is arranged to drive a centrifugal fan 9 having a central disk 8 and positioned within a flat boxlike housing 7 open at both ends, on the lower side of which are air inlet openings 6, 6 (Fig. 5). Within the housing 7 is an inner circular revolvable housing 5 contained and guided in part by the turned-in lips 4 of the top and bottom plates of housing 7 and in part by a pivot 19 extending through the top plate of housing 7.

This inner housing 5 comprises two diametrically opposite semi-circular bands or rings 2 and 3, open top and bottom, the upper band 2 being axially offset from the lower band 3, said lower band so arranged as to partially encircle the periphery of fan 9 so as to direct the fan discharge as desired and the upper band 2 arranged to determine from which direction the air flows to the upper fan blades. A stiffening member 11 is provided across the diameter of the revolvable housing 5. An operating handle 12, whereby the housing 5 may be revolved 180 degrees, extends from the two bands through the outer housing 7 as indicated (Fig. 5). A further stiffening member 20 lies across the open ends of band 2 providing a member through which the pivot 19 passes.

The outer housing 7 has a vertical dimension greater than the width of the fan, preferably twice the fan width, the intake space 13 above the plane of the top face of the fan arranged for flow of air from either end of the housing to the upper face of the fan. In operation, the upper band or baffle is positioned either to seal off space 13 from the

room air (Fig. 1) and open it to pass outside air or (Fig. 2) to seal off space 13 from the outside air and open it to pass room air to fan 9. At the same time, the diametrically opposite lower band 3 completes the enclosure of fan 9 in such way as to open the fan discharge to the area sealed off from intake by the upper band 2, as clearly indicated in Figs. 1 and 2.

Preferably, for window ventilation, the outer housing is supported as with screws 14, 14 to the upper part of the window casing 15. Telescoping side closure strips 18, 18 (Fig. 7) are provided, affixed as wing members to the housing 7, the upper sash 16 being lowered and weather strips 17 seal any cracks thus formed.

Preferably, also, the lower plate 1 of the outer fan housing 7, to which motor 10 is affixed, is a separate cast or stamped member or grille or a portion of it is so constructed, thus providing a separate removable sub-assembly comprising grille, motor and fan. It will be noted that for greater discharge efficiency of the fan when the ventilating device is acting to exhaust air from the space served (Fig. 2), a cut-off 21 (shown in Fig. 6) is provided within the housing 7, the edge of the housing or the edge of band 3 acting as a cut-off when discharge is to the space.

What I claim is:

1. A ventilator comprising a housing having top, bottom and end portions, driving means mounted on said housing and having a rotatable shaft projecting thereinto, a centrifugal impeller having blades and mounted on said shaft within said housing, a solid disc forming a part of said impeller bisecting each blade and dividing the impeller into upper and lower substantially identical sections, said housing including an opening in each of the opposite end portions thereof, baffle means for said openings disposed within said housing and movable about the axis of said shaft and means to operate said baffle means whereby alternate upper and lower portions of said openings are open or closed by said baffle means, said upper portions to flow of fluid to said impeller and said lower portions to tangential flow of fluid from said impeller.

2. A device according to claim 1 wherein said impeller has a central intake above and below said disc and has an axial width of substantially one-half that of the casing measured between the top and bottom portions.

3. A device according to claim 1 wherein said baffle means comprises two semi-cylindrical portions disposed one above the other and joined at their open ends, the lower portion of which is of substantially the same width as said impeller.
